UNITED STATES PATENT OFFICE.

SAMUEL E. DITTMAN, OF CHICAGO, ILLINOIS; WILLIAM E. DITTMAN ADMINISTRATOR
OF SAID SAMUEL E. DITTMAN, DECEASED.

UNDERLAY FOR PRINTING PLATES OR FORMS.

Application filed April 19, 1923. Serial No. 633,212.

My invention relates to an underlay for building up or leveling printing plates or forms and which forms, after the plates or forms have been leveled or built up, a seat 5 or backing for the plates or forms.

One feature of my invention resides in the provision of an underlay for leveling or building up printing plates or forms without injuring the printing faces thereof and 10 which, after the plates or forms are leveled or built up, provides a resilient seat or backing therefor whereby to afford a resilient printing contact. The underlay is particularly adapted for use directly on printing 15 presses and affords an extremely simple and effective means for building up or leveling a printing plate or form, its use materially decreasing the time and skill ordinarily required for "make ready" and at the same 20 time affording a much to be desired resilient printing contact.

Another feature resides in the provision of prepared underlay sheets of the above described character which are adapted to be 25 conveniently manufactured in large quantities and shipped and stored with a view toward commercial practicability and convenience to the consumer.

With these features and others, hereinafter appearing, in view the invention consists in the matters hereinafter fully described with reference to the accompanying drawings and more particularly pointed out in the 30 claims.

In the said drawings—

Figure 1 is an enlarged partial face view of a prepared underlay sheet.

Figure 2 is a section on the line 2—2 of Fig. 1.

Figure 3 is an enlarged partial face view of another form of sheet.

Figure 4 is a section on the line 4—4 of Fig. 3.

Figure 5 is an enlarged partial face view of another form of sheet.

Figure 6 is a section on the line 6—6 of Fig. 5.

Figure 7 is an exaggerated section of a plate and a prepared underlay sheet of the material on a printing press bed after the plate has been leveled or built up by means 50 of one of the underlay sheets.

Figure 8 is an enlarged partial face view of another form of underlay sheet.

Figure 9 is a section on the line 9—9 of Fig. 8.

Like characters of reference indicate like parts in the various views.

The underlay material of my invention is characterized by being permanently displaceable under pressure while applied to the back of a printing plate or form and by being resilient in displaced form to provide a resilient seat or back for the built up or leveled plate or form. The underlay material is preferably applied to the back of the plate in a displacement space providing pattern whereby the necessary pressure is decreased, whereby the displacement is localized, and whereby no portion of the plate is subjected to undue pressure. The pattern of the underlay material is preferably of uniform thickness and provides uniform displacement space for obvious reasons. A material which has these characteristics and which functions very well when applied to the back of a plate or form in a displacement space providing pattern consists of four parts flexible glue, four parts glycerine, one half part paraffine wax, one half part rubber cement, and one part water boiled together, the most important ingredients being flexible glue, glycerine, wax and water mixed together in suitable quantities and under suitable conditions to form the material having the above set forth characteristics.

Referring to the drawings, Figures 1—6 inclusive show the preferred embodiment of the prepared underlay sheets of my invention and showing various displacement space providing patterns of the material. In these figures 1 designates the displacement space providing pattern of the material, and 2 designates sheets of paper adhered, preferably by the adhesive qualities of the material 1, to opposite faces of the material and conforming with respective faces thereof. The paper sheets 2 may be substituted by any suitable material, such as cloth, and support the material in layer form and protect it. The paper sheets 2 are preferably oiled to prevent atmospheric conditions from affecting the material. Figures 8 and 9 show a prepared sheet in which only one sheet 2 of

paper or suitable material is adhered to a face of the pattern of material.

In the use of the prepared sheets to build up or level a plate or form, a prepared sheet is applied to the back of a plate or form 3, see Fig. 7, and the plate and prepared sheet are subjected to suitable pressure as by placing the plate and prepared sheet in desired position on the bed 4 of a printing press and subjecting them to pressure between the bed and impression element of the press. The material permanently displaces under the pressure and conforms the face of the plate with the impression element thereagainst and compensates for the varying thickness of the plate by displacing in accordance therewith, and where the material is displaced on the printing press it compensates for inaccuracies or irregularities of the press, plate base, and press packing. The displaced material forms a seat for the plate for printing therefrom and in displaced form is resilient and provides a resilient yielding printing contact.

The material as prepared does not need softening under ordinary circumstances but where it is desired to soften the material slightly a softening agent may be used such as water. Where the prepared sheet is used the softening may be effected by applying a sheet of moistened paper to one or both faces of the prepared sheet when the prepared sheet is applied to the back of the plate.

While I have herein described and shown one embodiment of my invention I do not wish to be limited to the precise details thereof as changes may readily be made without departing from the spirit of my invention but having thus described my invention I claim as new and desire to secure by Letters Patent the following:

1. An underlay for a printing plate or form comprising a displacement space providing pattern of resilient material permanently displaceable under pressure for leveling or building up a printing plate or form and providing in displaced form a resilient seat or backing for the plate or form.

2. An underlay for a printing plate or form comprising a displacement space pro-

viding pattern of resilient material permanently displaceable under pressure comprising flexible glue, glycerine, wax, and water combined in suitable quantities and under suitable conditions.

3. An underlay for a printing plate or form comprising a displacement space providing pattern of resilient material permanently displaceable under pressure comprising four parts of flexible glue, four parts of glycerine, one half part of paraffine wax, one half part of rubber cement, and one part of water boiled together to form the material.

4. An underlay for a printing plate or form comprising a displacement space providing pattern of resilient material permanently displaceable under pressure, and two sheets of suitable protective material adhered to opposite faces of the first mentioned material.

5. An underlay for a printing plate or form comprising a uniform displacement space providing pattern of uniform thickness of resilient material permanently displaceable under pressure and two sheets of paper adhered to and conforming with opposite faces of the material.

6. An underlay for a printing plate or form comprising a displacement space providing pattern of resilient material permanently displaceable under pressure comprising flexible glue, glycerine, wax, and water combined in suitable quantities and under suitable conditions and two sheets of oiled paper adhered to opposite faces of the material and conforming with opposite faces thereof.

7. An underlay for a printing plate or form comprising a uniform displacement space providing pattern of uniform thickness of resilient material permanently displaceable under pressure comprising four parts of flexible glue, four parts of glycerine, one half part of paraffine wax, one half part rubber cement, and one part of water boiled together to form the material and two sheets of oiled paper adhered to and conforming with opposite faces of the material.

In witness whereof I hereunto affix my signature this sixteenth day of April, 1923.

SAMUEL E. DITTMAN.
